(57) CLAIM

The ornamental design for a toilet brush, as shown and described.

DESCRIPTION

FIG. 1 is a perspective view of a toilet brush showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear side perspective view thereof; and,

FIG. 9 is an enlarged view of the area outlined in FIG. 1. The broken lines shown in FIG. 1 and 9 illustrate enlarged view indicators and form no part of the claimed design.

1 Claim, 9 Drawing Sheets
